UNITED STATES PATENT OFFICE.

JOSEPH O. BALDA, OF NEWARK, OHIO, ASSIGNOR TO A. H. HEISEY & CO., OF NEWARK,
OHIO.

DESIGN FOR A GOBLET OR SIMILAR ARTICLE.

Application filed December 16, 1922. Serial No. 4,625. Term of patent 14 years.

To all whom it may concern:

Be it known that I, JOSEPH O. BALDA, a citizen of the U. S. A., residing at Newark, county of Licking, and State of Ohio, have invented a new, original, and ornamental Design for a Goblet or Similar Article, of which the following is a specification, reference being had to the accompanying drawing in which—

Figure 1 is a side elevation of a goblet or similar article illustrating my invention, and

Figure 2 is a view similar to Figure 1, but showing the goblet and its surface ornamentation as they appear when observed from a different view-point, the two views together forming a panorama of the surface ornamentation as seen by the spectator.

I claim:—

The ornamental design for a goblet or similar article substantially as shown and described.

JOSEPH O. BALDA.
